Patented Dec. 11, 1888.

UNITED STATES PATENT OFFICE.

ALEXANDER P. COPP AND JOHN M. REMALEY, OF ROCHESTER MILLS,
PENNSYLVANIA.

STUMP-PULLER.

SPECIFICATION forming part of Letters Patent No. 394,155, dated December 11, 1888.

Application filed June 22, 1888. Serial No. 277,901. (No model.)

To all whom it may concern:

Be it known that we, ALEXANDER P. COPP and JOHN M. REMALEY, of Rochester Mills, in the county of Indiana, State of Pennsylvania, have invented a certain new and useful Improvement in Stump-Pullers, of which the following is a description sufficiently full, clear, and exact to enable any person skilled in the art or science to which said invention appertains to make and use the same, reference being had to the accompanying drawings, forming part of this specification, in which—

Figures 1, 2, and 3 are perspective views of our improved stump-puller represented as in use in different positions, a portion of the derrick and lever being shown as broken off in Figs. 2 and 3.

Like letters and figures of reference indicate corresponding parts in the different figures of the drawings.

Our invention relates to that class of stump-pullers which are designed to be operated by hand; and it consists in certain novel features, as hereinafter fully set forth and claimed, the object being to produce a more effective device of this character than is now in ordinary use.

The nature and operation of the improvement will be readily understood by all conversant with such matters from the following explanation:

In the drawings, A represents the framework of the stump-puller, which consists of three legs or standards, x, pivoted by their upper ends in brackets v on a key-block, z, and forming a tripod or derrick for supporting the lifting apparatus, hereinafter described.

A centrally-arranged supporting-bar, C, is suspended by means of a ring or hook, m, from the key-block z. A horizontally-arranged bifurcated lever, b, is pivoted to the upper portion of the bar C by a bolt, d. A bifurcated arm or brace, i, is secured to the bar C, one member only being visible in the drawings, and pivoted at 45 to said arm is a hand-lever, D, which is connected with the outer end of the lever b by a pivoted bar, h, thereby forming a compound lever. A ratchet-bar, H, is fitted to work between the inner end of the arms i. Two links, k, are pivoted by

their upper ends to the inner end of the lever b, the free ends of said links being adapted to engage the teeth q on the ratchet-bar H and lift said bar when raised by said lever. The 55 links k are constructed of different lengths, so that when the lever D, which actuates the lever b, is operated said links will engage the ratchet H alternately. A forked lever having curved arms s, j is pivoted at 60 to the 60 supporting-bar C, one arm, s, of said lever engaging the free end of the short link k, and the other arm, j, engaging the free end of the long link k. A coiled spring, 53, is secured by one end to the arm 61 of said forked lever, 65 and a chain, r, to the outer end of said spring, said chain being provided with a hook, 55, for securing it to a hook, 57, on the lever b, the purpose of said forked lever, spring, and chain being to disengage the links k from the teeth 70 of the ratchet H when the outer end of the lever D is elevated, as shown in Fig. 3, during the process of lowering the load, hereinafter described.

Supporting-links w are pivoted at one end 75 to the bar C, their outer or free ends engaging the teeth of the ratchet H. A forked lever having curved arms f, g is pivoted at 62 to the bar C, so that said arms will engage the free ends of the links w, a coiled spring, 54, 80 being secured by one end to the outer end of the straight arm 63 of said lever. A chain, y, provided with a hook, 56, for securing it to a hook, 59, on the lever D, is attached to the spring 54, said lever, spring, and chain being 85 designed to disengage the links w from the ratchet H when the lever D is depressed during the process of lowering the load, as shown in Fig. 2. A rod, 15, is detachably suspended from a hook, 25, secured to the key-block z, 90 and a chain, 16, upon which is disposed a sheave-block, 17, has one end secured in the lower end of the ratchet-bar H, the opposite end of said chain being secured in an eye, 18, on the lower end of the bar 15. A chain, 20, 95 provided with a hook, 21, is secured to the lower end of the supporting-bar C.

In the use of our improvement a chain, 23, is secured to the stump E, and a hook, 24, on the sheave-block 17 inserted in said chain, 100 the derrick A having been adjusted in position over said stump, after which the rod 15

is secured to the key-block z , as described. The hooks 55 and 56 are detached from the hooks 57 and 59 on the levers b and D and hang suspended, as shown in Fig. 1, during 5 the process of lifting. By depressing the lever D , and thereby elevating the short arm of the lever b , a link, k , pulls the ratchet-bar H upward and gradually tightens the chain 16. As the lever D is released or raised to repeat 10 the operation, thereby detaching said link from said ratchet, a link w holds said ratchet-bar in the position it has attained until another link, k , engages it and draws it still farther upward as said lever is again de- 15 pressed.

It will be understood that the links k and w are held in engagement with the teeth q of the ratchet-bar H by their own weight, and by constructing the links k of different 20 lengths, as described, they alternately engage a tooth of said ratchet-bar at each downward motion of the lever D , the links w meanwhile supporting said ratchet-bar and preventing it from slipping downward, so that no motion is 25 lost during the interval of raising said lever to obtain a new hold on said bar.

By securing an ordinary grappling-chain to the stump and fastening it to the hook 21 on the chain 20 the stump may be sustained in 30 the position to which it has been elevated when it becomes necessary to attach the chain 23 to some other portion thereof in order to 35 loose the roots.

By employing the rod 15, adjusted as de- 35 scribed, a great portion of the lifting strain is transferred from the ratchet-bar H directly to the derrick.

It will readily be seen that by the use of the compound lever D and the sheave-block 40 17 sufficient leverage is obtained to overcome great resistance with the expenditure of a very small amount of power.

By distributing the lifting strain as de- 45 scribed, so that the ratchet H and supporting bar C are relieved of a large portion thereof, a much lighter apparatus may be employed to perform the same work than is possible in stump-pullers when constructed in the ordinary manner.

50 When it is desired to lower the load raised, as above described, the hooks 55 and 56 are connected, respectively, with the hooks 57 and 59 on the levers b and D . The lever D , being then depressed, causes the spring 54 to be 55 distended, and thereby forces the curved arms f g of the forked lever 62 against the free ends of the links w , disengaging said links from said ratchet, as shown in Fig. 2. The lever D being then elevated, as shown in Fig. 3, the 60 ratchet-bar H is permitted to fall several notches before the spring 54 is relieved sufficiently to enable the links w to again engage said ratchet and support the load. By continuing the upward motion of the lever D 65 above the plane of the arm i the curved arms

s , j are caused to engage the free ends of the lifting-links k and force them out of engagement with said ratchet, as shown in Fig. 3, so that when the downward motion of the lever D is resumed and continued sufficiently to 70 cause the spring 53 to be released said links will again engage said ratchet several teeth above where they were last engaged. By continuing to oscillate the lever D it will be seen that the load will be quickly lowered to the 75 ground, the operation of the links upon the ratchet being diametrically opposite to that by which the load is raised.

Having thus explained our invention, what we claim is—

80

1. In an apparatus of the character described, the combination of the tripod-derrick A , the pendent supporting-bar C , secured to said derrick, the arms i , secured to said bar, the lever D , pivoted to said arms, the 85 lever b , pivoted to said bar, the arm h , pivoted to said levers, the ratchet-bar H , the links w , pivoted to the bar C , for supporting said ratchet-bar, the links k , pivoted to the lever b and adapted to alternately engage the teeth 90 of said ratchet and elevate the same, a forked lever pivoted to the bar C and having the curved arms s , j , for disengaging the links k from said ratchet, the spring 53, connecting said forked lever with the lever b , a forked 95 lever provided with curved arms f , g , for disengaging the links w from said ratchet, the spring 54, connecting said forked lever with the lever D , and a chain for securing said ratchet-bar to the object to be lifted, substantially as set forth.

2. In an apparatus of the character described, the combination of the tripod-derrick A , having the block z , the pendent bar C , secured to said block, the arms i , secured to said bar, the lever D , pivoted to said arms, the lever b , pivoted to said bar, the arm h , connecting said levers, the ratchet-bar H , the links k , pivoted to the lever b and adapted to alternately engage said ratchet, the links w , pivoted to the bar C , for supporting said ratchet, the chain 16, secured to the lower end of said ratchet, the rod 15, secured to said chain and derrick, the sheave-block 17 on said chain, a forked lever having the arms s , j pivoted to 110 the bar C and connected with the lever b , and a forked lever having the arms f , g pivoted to the bar C and connected with the lever D , the arms of said forked levers respectively engaging the links k , w , and disengaging them 115 from said ratchet when said levers b , D are operated, substantially as specified.
